UNITED STATES PATENT OFFICE.

OTTO L. HERMANN, OF ST. LOUIS, MISSOURI, ASSIGNOR TO BUXTON & SKINNER PRINTING AND STATIONERY COMPANY, OF ST. LOUIS, MISSOURI, A CORPORATION OF MISSOURI.

SHEET HOLDER FOR LOOSE-LEAF BINDERS.

Application filed March 13, 1926. Serial No. 94,400.

My invention relates to devices for holding loose-leaf binder sheets during the operations of removing sheets from the binder and inserting them in the binder. It is particularly adapted for use with the type of binder having a multiplicity of straight posts and using comparatively short sheets that extend only a portion of the length of the binder and are provided with a multiplicity of holes spaced apart even fractions of the distance between binder posts, whereby each sheet may have any one of a multiplicity of positions in the binder. The invention has for its object to facilitate the handling of the sheets during the operations of removing sheets from the binder and inserting them in the binder. The invention consists principally in a sheet holder having notches (or projecting fingers) along one edge, said notches being adapted to fit over the binding posts and a clamp at the other edge of said sheet holder adapted to hold a number of sheets. The invention further consists in the sheet holder and in the parts and combinations and arrangements of parts hereinafter described and claimed.

In the accompanying drawing,

Figure 1 is a perspective view of a loose-leaf binder and a sheet holder therefor embodying my invention;

Fig. 2 is a plan view thereof; and

Fig. 3 is a detail sectional view on the lines 3—3 of Fig. 2 showing the clamp mechanism of the sheet holder.

In the drawing is illustrated a loose-leaf binder A comprising cover members 1 hingedly secured together and each provided with a multiplicity of straight pins or binding posts 2. In the binder are groups of comparatively short sheets 3, such as ledger account sheets or the like, arranged alphabetically, or according to any desired system. Said sheets 3 have a multiplicity of holes 4 along one margin adapted to fit over the binding posts 2, so that each sheet may be placed in different positions in the binder. In practice, the sheets 3 are arranged in groups, each sheet of a group projecting at the bottom (or top) beyond the preceding (or following) sheet, thereby leaving a strip 5 of each sheet of the group exposed, on which exposed strip appears the name or other word by which the sheet

is indexed. When the sheets are first put in the binder, each group will ordinarily be composed of a number of sheets 3 insufficient to extend from the top to the bottom of the binder. Thus, if it is desired to insert an additional sheet or sheets in any one group, the insertion can be made merely by moving some of the sheets of the group and it will not be necessary to carry the adjustment to other groups of sheets. In addition to the short sheets 3, the binder will ordinarily be provided with full sized partition sheets 6 marked with the letters of the alphabet or other suitable indexing memorandum. The posts 2 of one cover member of the binder are preferably staggered with respect to the posts of the other member of the binder, so that they will pass through different holes 4 in the sheets 3.

When it is desired to insert an additional sheet 3, (or sheets) it is necessary to open the binder to the proper group and remove the sheets preceding the point where the additional sheet is to be inserted, put the additional sheet (or sheets) in position and then replace the sheets that were temporarily removed, such sheets, however being moved to a different position depending on the number of sheets removed. Likewise if a sheet is to be removed permanently it is necessary to remove temporarily the sheets preceding it in the group, then remove the desired sheet and replace the sheets that were temporarily removed, such sheets being moved down a step to fill the gap left by the removal of the sheet.

The drawing illustrates a binder A open to permit insertion of sheets 3 in or removal of sheets from a group. The indexing sheet 6 at the top of the group is opened with the opened cover member, leaving exposed the group of sheets 3 in which the change is to be made.

The making of such a change frequently results in tearing of sheets and in disarrangement thereof; and the present invention is a sheet holder B facilitating the making of the change. Said sheet holder comprises a plate 7 having a multiplicity of projecting fingers 8 along one edge, thereby forming notches 9 or recesses adapted to fit over binding posts 2 of the binder. Said recesses 9 are spaced apart even fractions of the distance between binding posts 2 and are

comparatively close together, and the end portions of the fingers 8 are rounded off, whereby it is easy to slip the sheet holder into a position where binding posts are received in notches thereof. Along the edge of the sheet holder B opposite the recesses is a clamping device 10 provided with a spring 11 tending to hold it in engagement with the plate, and adapting it to engage sheets on the holder and hold them thereon.

If it is desired to insert an additional sheet, the holder B is placed beneath the sheet just preceding the point where the additional sheet is to be located. The clamp 15 is opened and the holder B pushed to the side until some of the notches 9 thereof fit over binding posts 2 and the edges of the sheets 3 are brought into the clamping device 10. The body of the plate 7 is of such 20 width that when the bottoms of the notches 9 rest against the binding posts 2, the edges of the sheets 3 are under the clamp 10 in position to be engaged thereby. Then the clamp 25 10 is permitted to engage the sheets 3 to hold them on the plate 7 and the holder is raised, carrying with it the sheets. The projecting fingers 8 support the marginal portions of the sheets 3. The new sheet 3 is then placed in position in the binder and 30 the holder is positioned over the proper binding posts and then lowered, permitting binding posts 2 to enter holes 4 of the sheets, thus positioning the sheets that were temporarily removed, so that the lowermost 35 sheet is placed over the newly added sheet, leaving a narrow marginal strip of such newly added sheet exposed. The bringing of notches 9 of the plate into alignment with binding posts 2 likewise brings holes 4 of the 40 sheets into alignment with binding posts 2, so that the sheets are easily put into the binder.

If a sheet is to be removed, the holder will be inserted beneath the sheet just preceding 45 said sheet that is to be removed and all of the preceding sheets of the group will be lifted from the binder as above described. Then the sheet is removed and the preceding sheets reinserted in the binder, the lowermost sheet of those that were temporarily 50 removed taking the position of the sheet that was removed (that is one step lower than its former position) and the other sheets of the group likewise being moved 55 down along with the lowermost sheet.

Where a number of sheets such as those herein illustrated are removed in the ordinary way, it is very difficult to maintain them in proper position, since they are arranged in stepped relation. Accordingly, 60 it is quite difficult to place the sheets in the binder and to properly fit the holes thereof over the binding posts. The use of the sheet holder herein described maintains the sheets 65 in proper arrangement while they are out of

the binder and makes it easy to replace them in the binder; and it avoids the danger of tearing the sheet due to canting or twisting them in removing them from the binding posts or replacing them thereon; since the 70 binding posts fitting in the notches guide the holder and make it easy to raise and lower it.

What I claim is:

1. A device of the kind described comprising a plate adapted to support a plurality of perforated sheets and a clamp for holding such sheets on the plate, said plate being provided with a multiplicity of recesses along one edge adapted to receive binding posts of a binder, the spaces between said recesses and the spaces between said perforations in said sheets being equal to each other and less than the spaces between said binding posts, the spacing of said recesses conforming to the spacing of the holes of said sheets.

2. A sheet holder adapted for use with a binder having a multiplicity of posts and using comparatively short sheets each having a multiplicity of perforations adapted to receive said binding posts, said sheet holder comprising a plate adapted to support a plurality of sheets arranged so that a marginal portion of each sheet extends beyond the adjacent sheet and a clamp for holding such sheets on the plate, said plate being provided with a multiplicity of recesses along one edge adapted to receive binding posts of the binder, the spaces between recesses and the spaces between said perforations being equal to each other and less than the spaces between said binding posts, the spacing of said recesses conforming to the spacing of the perforations of said sheets.

3. A sheet holder adapted for use with a binder having a multiplicity of posts and using comparatively short sheets each having a multiplicity of perforations adapted to receive said binding posts, said sheet holder comprising a plate adapted to support a plurality of sheets and a clamp for holding such sheets on the plate, said plate being provided with a multiplicity of recesses along one edge adapted to receive binding posts of the binder, said recesses in said plate and said perforations in said sheets being spaced apart even fractions of the distance between binding posts.

4. A sheet holder adapted for use with a binder having a multiplicity of straight posts and using comparatively short sheets each having a multiplicity of perforations adapted to receive said binding posts, said sheet holder comprising a plate adapted to support a plurality of sheets and a clamp along one edge for holding such sheets on the plate, said plate being provided with a multiplicity of fingers along the edge opposite said clamp, said fingers constituting the

marginal walls of recesses adapted to receive binding posts of said binder, said recesses in said plate and said perforations in said sheets being spaced apart even fractions of the distance between binding posts and the ends of said fingers being rounded off to guide said binding posts on said recesses.

5 5. A sheet holder adapted for use with a binder having a multiplicity of straight posts and using comparatively short sheets each having a multiplicity of perforations adapted to receive said binding posts, said sheet holder comprising a plate adapted to support a plurality of sheets and a clamp along one edge of the plate for holding such sheets thereon, said plate being provided with a multiplicity of recesses along the edge

opposite said clamp adapted to receive binding posts of the binder, the distance between the clamping edge of said clamp and the bottoms of said recesses in said plate being less than the width of said sheets measuring from one edge thereof to the bottoms of the perforations along the opposite edge, whereby when said sheet holder with the clamp open is inserted beneath sheets of a binder and positioned with binding posts of the binder resting in the bottoms of recesses in the plate, the edges of such sheets extend into said clamp in position to be engaged thereby.

Signed at St. Louis, Missouri, this 10th day of March, 1926.

OTTO L. HERMANN.
